US00D847195S

(12) **United States Design Patent** (10) Patent No.: **US D847,195 S**
 Sellers et al. (45) Date of Patent: **** Apr. 30, 2019**

(54) **DISPLAY SCREEN WITH GRAPHICAL USER INTERFACE**

(71) Applicant: **Gamblit Gaming, LLC**, Glendale, CA (US)

(72) Inventors: **David Sellers**, South Pasadena, CA (US); **Zachary Foley**, Los Angeles, CA (US)

(**) Term: **15 Years**

(21) Appl. No.: **29/600,577**

(22) Filed: **Apr. 13, 2017**

Related U.S. Application Data

(63) Continuation of application No. 29/574,874, filed on Aug. 19, 2016, which is a continuation of application No. 29/540,638, filed on Sep. 25, 2015, now Pat. No. Des. 777,194.

CLAIM

The ornamental design for a display screen with graphical user interface, as shown and described.

DESCRIPTION

FIG. 1 is a front view of a first embodiment of a display screen with graphical user interface, showing our new design; and,

FIG. 2 is a front view of a second embodiment of a display screen with graphical user interface, showing our new design.

The broken lines showing the electronic device illustrate environmental structure. All other broken lines illustrate portions of the display screen with graphical user interface. No subject matter depicted in any of the aforementioned broken lines forms part of the claimed design.

1 Claim, 2 Drawing Sheets
